ANTIFLAPPING DEVICE FOR PORCH
CURTAINS

George A. Phinn, Pasadena, Calif.

Application May 7, 1934, Serial No. 724,287

5 Claims. (Cl. 156—26)

This invention relates to means for securing curtains against flapping and damaging vibration usually set up by the action of wind and the objects of the invention being to provide a simple and inexpensive device which is economical to make, may be readily installed or applied to a window or door frame, and will effectively engage and press the curtain material against the frame with relation to which it operates. The invention is designed chiefly for that type of curtain known as "drop roll curtains" in which the roll of curtain material itself is lowered and elevated to cover or uncover the space behind it, as distinguished from the spring roller curtain. In the "drop roll" type obviously the curtain or curtain material may be and usually is of considerable area and is applicable to porches, verandas and other places of extent greater than that which could be protected or covered by a spring roller curtain.

Other objects will appear from the specification following in connection with the accompanying drawing in which

Fig. 1 is a front elevation of a device embodying my invention.

Fig. 2 is a side elevation showing the invention as applied to a frame, dotted lines indicating elevated position of the curtain and the inoperative position of the fixture.

Fig. 3 is a front elevation of a window and its frame and of the devices as attached thereto, and

Fig. 4 is a plan view of one of the elements oscillatably mounted on each end of the curtain pole to act as a guide for the flexible wire or rope that holds the roll of curtain material firmly against the frame.

Referring in detail to the drawing, 1 designates a bracket, in the nature of a post that is provided with a base plate 2, arranged to be secured to a suitable frame 3. The post or bracket 1 extends outwardly from the frame 3 and, as shown in Fig. 1 the end 4 of same is bent at right angles upon itself and forms a mount for a bar 5 that is rigidly secured in vertical position to the horizontal or bent portions 4 of the bracket 1. The bar 5 is provided with trunnions 6 for pivoting a frame 7, which as shown in Fig. 1 is composed of two plates. These plates, which are in substantially the shape of a bell-crank, except that the upper leg 7' is considerably longer than the lower leg 7'', are held spaced by said bar 5 and four rods 8', 9', 10' and 11', the rod 11', journaling a roller 11 in the end of the lower leg 7'' of the frame 7 and the rods 8' and 9' respectively journaling rollers 8 and 9 in the longer upper leg of

the frame 7. To the rod 10' is anchored one end of a helical spring 12; the other end of said spring is fastened to said bar 5, which is slotted as at 13 to permit passage therethrough as the frame 7 is oscillated as hereinafter described and the spring is thereby caused to exert its tension on one side or the other of its neutral center which is the bar 5. The upward movement of the frame 7 to the position indicated in dotted lines Fig. 2 is automatically completed by said spring 12 and such movement of the frame is limited by stop members 14 formed or provided on the frame plates, these stop members being arranged to strike against the upstanding bar 5. The downward movement of said frame 7 to the position shown in Fig. 2 is completed by said spring 12, and this downward movement is limited by the impingement of the roller 8 in and projecting beyond the end of the frame 7 against the curtain material 15 in which position the roller 8 is held in yielding contact with the curtain 15 by the spring 12 and presses it with yielding pressure against the frame or casing 3. The upper leg 7' of the bell-crank frame 7 is, for this reason, made longer than the bracket 1 to which it is operatively connected. When the end roller 8 is not in contact with any restraining object, as pointed out, the movement downwardly is limited by the lower leg 7'' of the frame which strikes against the portion 4 of the bracket; but in actual practice the engagement of the roller 8 with the curtain holds the lower leg 7'' away from contact with the portion 4 of the bracket and being under the tension of said spring 12, such engagement is a yielding one. The curtain, 15 is wound upon a pole 16 and is in the normally inoperative position, shown in dotted lines in Fig. 2, having been elevated from the position shown in full lines Fig. 2, by ropes or cables 17, that are fastened at one end to the top of the casing or frame 3 and after passing under the rolled curtain, are run over pulleys 18. During the elevation of the roll of curtain 15, the roller 9 of the longer leg 7' of the bell-crank or frame 7 has been engaged by the diametrically increasing roll 15' and thrust it upward to the position where the spring 12 tends to complete the movement as shown in dotted lines Fig. 2. At the same time, the shorter leg 7'' is thrown inwardly toward the frame or casing 3, and in the direct path of movement downwardly of the roll, which, engaging it, causes the frame 7 to oscillate and the spring 12 to force the roller 8 in the longer leg 7' of the frame to contact the unwound portion of the curtain, which is thereby held against vibration and other

annoyances due to winds. The curtain pole 16 is provided with sheaves 19 and with guides 20 fitting over said sheaves 19, for tensioned cables or ropes 21 that are arranged to press against said sheaves 19 and hold the curtain securely against the casing or frame.

What I claim, is:

1. A device for holding a curtain against its frame to prevent flapping thereof, comprising in association with such frame and such curtain a bracket attachable to said frame and having a bent portion extending over the edge of and outwardly from the face of the curtain, a bar rigidly secured to and upstanding from, said bent portion, a frame trunnioned on said bar and having a long leg and a short leg at substantially right angles to each other, a roller journaled in the end of each of said respective legs, a spring connecting said frame with said upstanding bar and actuatable on either side of said bar to maintain the roller in the end of said longer leg in yielding engagement with the curtain at one time and out of engagement at another time, said frame being tiltable to engaging position with the curtain by the movement of the curtain roll in one direction and out of engaging position by the movement of said curtain roll in another direction.

2. A device for holding a porch curtain against a frame to prevent flapping thereof comprising, in association with such frame and curtain, a bracket attachable to such frame and extending outwardly therefrom, said bracket having a bent portion, a bar secured to said bent portion, a frame trunnioned on said bar and tiltable with respect thereto, said frame provided with a curtain engaging roller, a spring to hold said frame on either side of the center of said bar, said frame operable by the movement of the curtain roll to engaging or disengaging position, and means to limit the tilting movement of said frame relatively to said bar.

3. A device for holding a movable roll porch

curtain against casing to prevent flapping thereof, comprising, in association with said casing and the curtain, a frame composed of an upper curved leg and a shorter lower leg at substantially right angles to each other, a curtain engaging roller journaled in the respective end of said frame, a roller journaled intermediate said upper leg, a bracket secured to the casing, said frame being trunnioned on said bracket and a spring to move and hold said frame on either side of its pivotal center, said intermediate roller being engageable by the curtain roll to move said upper leg out of its path and said lower leg being engageable by said roll to move the upper leg into its path.

4. A device for holding a porch curtain against a casing to prevent flapping thereof comprising in association with such casing and the curtain, a bracket securable to and extending outwardly beyond and over the edge of the curtain, a frame trunnioned on said bracket, said frame having a curving upper branch carrying in the end thereof a roller and a lower branch carrying in the end thereof a roller, stop means on the curving branch to limit the arcuate movement upwardly thereof, said bracket serving to limit the arcuate movement downwardly of said branch, and a spring tending to hold said frame tilted in either position.

5. A device for holding a movable roller curtain against vibration comprising a bracket, a frame trunnioned on said bracket, and having two branches at substantially right angles to each other, one of said branches being longer than the other and journaling a curtain engaging roller, stop means for limiting the movement of said frame, and a spring to hold said frame against either of said stop means, said frame being operable by the curtain roll to move the longer branch thereof to engaging or disengaging position.

GEORGE A. PHINN.
